UNITED STATES PATENT OFFICE.

WILLIAM W. HODGSON, OF CHICAGO, ILLINOIS, ASSIGNOR TO CONTINENTAL CAN COMPANY, INC., OF NEW YORK, N. Y., A CORPORATION OF NEW YORK.

METAL CONTAINER.

Application filed March 15, 1927. Serial No. 175,494.

The invention relates to new and useful improvements in metal containers, and more particularly a metal container wherein one end is hermetically secured to the body portion of the container by a sealing member that can be easily ruptured and removed.

An object of the invention is to provide a container of the above type wherein the outer portion of the flange on the can end is folded underneath and against the under surface of the flange and extends across and is shaped to conform to the rolled flange on the body portion of the container, whereby the spring of the metal in the folded back portion of the flange aids in the securing of a tight seal.

In the drawings—

Figure 1 is a sectional view through a sealed container embodying the improvements, and

Fig. 2 is an enlarged sectional view of the parts of the container separated from each other and prior to the rolling of the flange on the sealing ring into sealing engagement with the body portion of the container.

The invention is directed to a container of the type shown in the patent granted Messrs. Coyle & Taliaferro, January 6, 1925, No. 1,521,599. The container consists of a body portion having a rolled flange which is preferably hollow so as to be slightly resilient. The can end for closing the body portion is provided with a depending portion which is adapted to frictionally engage the inner wall of the body portion. Said end is also provided with a flange which extends over the flange on the body portion and the outer portion of this flange on the end is folded underneath and against the under face of the flange on the can end. This underneath folded portion extends all the way across the rolled flange on the body portion and is shaped to conform to said flange on the body portion. The sealing material is placed between this folded back portion of the flange on the end and the rolled portion on the body. When the sealing ring is placed about the flanges, it will bind the metal parts in tight sealing engagement with each other.

Referring more in detail to the drawings, my improved container consists of a body portion 1 having an outwardly rolled flange 2 which is preferably hollow. The can end 3 is provided with a depending portion 4

which is adapted to frictionally engage the inner wall 5 of the body portion of the container. Said end has an outwardly extending flange 6 which overlies the rolled flange on the can body. This outwardly extending flange on the can end is folded underneath as indicated at 7, and against the under face of the flange. The portion 7 extends all the way across the rolled flange 2 and is curved to conform to the curvature of the rolled flange. The sealing material 8 for sealing the container is applied to the under face of this portion 7 and lies between this portion 7 and the outer upper face of the rolled flange 2. The end is secured to the container for sealing the same by an integral sealing ring having a substantially horizontal portion 9 formed with a vertical depending wall 10. The sealing ring is provided with an inwardly projecting member 11, which may be used for rupturing the sealing ring. The can end is placed on the container body, after which the sealing ring is placed on the flanges, and the lower portion 12 of the vertical wall 10 is rolled underneath the hollow flange 2. The sealing ring is pressed down on to the can end and the can end and body portion held in tight contact with each other when the seaming tool is applied to the lower portion of the sealing ring for rolling the same underneath the hollow flange on the container body.

The portion 7 is turned underneath the flange on the can end in the forming of the can end, which, of course, is accomplished on a die press. There is always a certain amount of spring back in the metal, so that there is a tendency of the portion 7 to spring away slightly from the underneath face of the flange 6. Likewise, there is a slight flexing of the circular outside sealing ring when the parts are released from the tools operating thereon. Inasmuch as the sealing material is on the under face of this portion 7, and between the same and the hollow bead on the container body, this slight springing away of the turned underneath portion on the can end will force the same into contact with the sealing material and the sealing material into contact with the hollow bead on the container body throughout the entire extent thereof. This aids in the maintaining of a very tight seal, so that the contents of the container may be put

2
up under considerable pressure, or considerable vacuum, if desired, without there being any leaks.

Having thus described the invention, what I claim as new and desire to secure by Letters-Patent, is—

A sealed metal container comprising a body portion having an outwardly rolled flange, an end having a depending portion 10 adapted to frictionally engage the inner wall of the body portion and an outwardly extending flange overlying the flange on said body portion, the outer portion of said flange on the end being folded underneath and 15 against the under face of the flange, said underneath portion extending across and being shaped to conform to and engage the rolled flange on the body portion, said un-

derneath portion terminating at said depending portion on the end, a sealing material located between the underneath portion and the rolled flange on the container body, and a sealing ring having a portion adapted to overlie the flange on the end, a portion extending downwardly across the 25 edges of the flanges on the end and body portion of the container, and adapted to be turned under and against the lower portion of the flange on the container body so as to grip and hold said flanges in tight sealed 30 contact, and means whereby said sealing ring may be torn across to release the same from the container.

In testimony whereof, I affix my signature.

WILLIAM W. HODGSON.
